UNITED STATES PATENT OFFICE

1,924,640

LUMBAGO BELT

Rudolph Draves, Bonners Ferry, Idaho

Application June 2, 1930. Serial No. 459,007

1 Claim. (Cl. 128—95)

This invention relates to supporting belts; and more particularly, to a belt adapted to be applied in supporting pressure to the spinal column for the relief of lumbago and other similar ailments.

5 An object of the present invention is to provide a device of the character indicated adapted to be worn adjacent the body or underclothing, providing a maximum support precisely where desired, with means for adjusting the pressure to suit

10 the wearer's condition.

Further objects will more particularly appear in the course of the following detailed description.

The invention consists in the novel construction, arrangement and combination of parts as hereinafter more particularly described and claimed.

15 One sheet of drawings accompany this specification, as part thereof, in which like reference numerals indicate like parts throughout.

Figure 1 is a perspective view of the improved belt, not applied, but arranged in a position similar to that in which it is applied;

Figure 2 is a fragmentary back view of the belt 25 and pad;

Figure 3 is a vertical cross section taken on line 3—3 of Figure 2;

Figure 4 is a view similar to Figure 3 showing the adjusting key in position to augment the 30 effect of the rib;

Figure 5 is a fragmentary cross section taken on line 5—5 of Figure 2; and

Figure 6 is a view similar to Figure 5, showing the adjusting key in position.

35 Referring to the drawing, a belt 1 is provided having a buckle 2 secured to one end and having holes spaced apart in the other end for cooperating with the buckle, by means of which the belt can be adjusted with a suitable tightness about 40 the body of the wearer.

Secured to the interior face of belt 1 substantially medially thereof is a pad 4, preferably constructed of leather or similar flexible material and of a substantially rectangular shape. The 45 pad 4 is positioned on the belt 1 by passing the belt behind the same and along one of its diagonals, and the belt and pad are secured together by stitches 6 extending inwardly from each of the corners of the pad which overlay the belt, 50 but which stitches 6 do not meet centrally of

the pad but terminate to provide a centrally positioned pocket 7 intermediate the pocket and pad in line with its vertical axis.

A rib 5 of leather or similar flexible material is positioned upon the inner face of pad 4 in 55 alignment with its vertical axis and perpendicular to the belt, which rib 5 is adapted to seat in the curvature of the back and against the spinal column.

A key 8 of leather, or the like, is provided 60 adapted to seat in pocket 7 intermediate the belt and pad 4 and directly back of rib 5. The key 8 is preferably provided with projecting lug 9 to increase its thickness, and if desired, a plurality of such lugs of varying thicknesses can be provided.

65 Key 8 is provided at one end with a hole 10 by means of which and a cord 11 it may be retained in relation to the belt to avoid loss.

It will be apparent that without positioning 70 key 8, rib 5 will normally exert a slight pressure against the spinal column. This pressure can be increased by inserting key 8 up to the lug 9 and can be still further increased by inserting the key beyond lug 9 in the pocket 7, as is well illustrated in Figures 3, 4, and 6.

75 Various modifications in the precise shape and construction of the parts as well as in the material will readily suggest themselves to those skilled in this art, but within the scope of the 80 present invention, as claimed.

Having thus fully described my invention, I claim:

An orthopedic appliance comprising: a pad, 85 a rib on the inner surface of said pad adapted to fit along the spinal column, a belt passing over the outer surface of said pad and secured at spaced points on the rear surface of said pad so as to form a loop on the outer face of the pad between its opposite edges, and a key adapted to 90 be removably inserted in said loop to increase the pressure of said pad against the spinal column, said key having a projecting lug secured thereto between its ends, the lug being adapted to engage said loop in one position of the key 95 to act as a stop to limit the insertion of the key in said loop, and also being adapted to be placed within said loop to further increase the pressure of said pad against the spinal column.
